UNITED STATES PATENT OFFICE.

JAMES M. KING, OF CHESTER, NEBRASKA, ASSIGNOR OF ONE-HALF TO JOHN W. MENDENHALL AND JOHN P. BEERMACKER, OF SAME PLACE.

DEVICE FOR DEHORNING CATTLE.

SPECIFICATION forming part of Letters Patent No. 411,895, dated October 1, 1889.

Application filed May 9, 1889. Serial No. 310,171. (No model.)

To all whom it may concern:

Be it known that I, JAMES M. KING, a citizen of the United States, residing at Chester, in the county of Thayer and State of Nebraska, have invented a new and useful Dehorning Device, of which the following is a specification.

This invention relates to devices for dehorning cattle; and it has for its object to provide an implement by means of which the operation of dehorning may be performed in a safe, rapid, and effective manner.

The invention consists in the improved construction and arrangement of parts, which will be hereinafter fully described, and particularly pointed out in the claims.

In the drawings, Figure 1 is a perspective view of my improved dehorning apparatus, showing the shears open. Fig. 2 is a side view taken from the opposite side of the same, with the shears shown closed. Fig. 3 is a transverse sectional view.

The same letters refer to the same parts in all the figures.

25 A designates a rod or handle, to the upper end of which, on opposite sides thereof, are secured a pair of metallic bars B B, which may be fastened to the said handle by means of transverse bolts or rivets C C, and the lower ends of which are turned outwardly, so as to form shoulders or offsets D D. The ends of the bars B B are bent slightly in a rearward direction, and between their upper or outer ends is pivoted the end of the shank E of the 30 movable knife or cutter F.

35 G designates a metallic bar or plate, to the lower end of which is pivoted or otherwise suitably attached a ring H, which encircles the rod or handle A. At the upper or outer end of the bar G is formed a hook-shaped knife or cutter I, the base of which is pivotally connected with the cutter F by means of a bolt or rivet J. The point of the hook-shaped cutter I is connected with the shank 40 or bar G by means of metallic straps K K, secured by means of rivets L, and between which the point of the knife or cutter F is guided.

45 Suitably secured to the rod or handle A is a laterally-extending handle M, by means of which the operator is enabled to get a firm hold upon the implement.

In operation the ring H at the lower end of the shank or bar G is slid in a downward direction upon the handle A, thus separating the cutting-edges of the knives or cutters F 55 and I, the former of which swings back to the position shown in Fig. 1 of the drawings. The hook-shaped cutter is then adjusted over the horn of the animal close to the head, when by pulling swiftly and forcibly upon the handle 60 A the cutting-edges of the knives F G will be brought together and the horn severed from the head of the animal. The shoulders or offsets D D at the lower ends of the bars B B form stops, by means of which the ring H is 65 prevented from sliding too far upwardly after the edges of the cutters have slightly passed each other. The straps K K not only form guides for the point of the pivoted cutter F, whereby the cutting-edges of the cutters are 70 prevented from being spread apart, but they also act in the nature of braces to prevent the hook-shaped cutter from yielding to pressure exerted thereon. The device is exceedingly simple in construction, and with its assistance the operation of dehorning may be 75 performed rapidly, safely, and in the most humane manner.

Having thus described my invention, I claim—

1. In a device for dehorning cattle, the combination of a hook-shaped knife or cutter, plates or braces connecting the point of said cutter with the shank of the same, and a knife or cutter attached pivotally at the base of said 85 hook-shaped cutter, with its point sliding between the said plates or braces, substantially as set forth.

2. The combination of a rod or handle, the metallic bars or straps attached to the sides 90 of the same and having their lower ends bent outwardly to form shoulders or offsets, a knife or cutter having the outer end of its shank mounted pivotally between the outer ends of said straps, a hook-shaped knife or 95 cutter, a bolt or rivet connecting the said knives or cutters at their respective bases, and a ring suitably attached to the shank of the hook-shaped cutter for the passage of the rod or handle, substantially as set forth.

3. In a device for dehorning cattle, the combination of a hook-shaped cutter, straps or

- braces connecting the point of the same with the shank thereof, a cutter mounted pivotally at the base of the said hook-shaped cutter, a handle having upwardly-extending straps, 5 the outer ends of which are connected pivotally with the outer end of the shank of the pivoted cutter, and a ring or guide for said handle at the lower end of the shank of the hook-shaped cutter, substantially as set forth.
- 10 4. In a device for dehorning cattle, the combination of a hook-shaped cutter, straps or braces connecting the point of the same with the shank thereof, a cutter mounted pivotally at the base of said hook-shaped cutter, a ring 15 suitably attached to the shank of the latter,

and a rod extending through said ring and having a laterally-extending handle and upwardly-extending straps, the outer ends of which are connected pivotally with the outer end of the shank of the pivoted cutter, and 20 the lower ends of which are bent outwardly so as to form shoulders or offsets, substantially as and for the purpose set forth.

In testimony that I claim the foregoing as my own I have hereto affixed my signature in 25 presence of two witnesses.

JAMES M. KING.
